[57] CLAIM

The ornamental design for dual data station for distributed data system, as shown.

DESCRIPTION

FIG. 1 is a perspective view showing the top, left side and one display face of a dual data station for a distributed data system incorporating my new design.

FIG. 2 is a right side elevation of said dual data station.

FIG. 3 is an elevation showing the other display face of said dual data station.

FIG. 2

FIG. 3
